 New York, N. Y., a corporation of New York

Application May 18, 1943, Serial No. 487,439

2 Claims. (Cl. 58—26)

1

This invention relates to clocks and more particularly to a clock of the type wherein its time indicating element, or elements, is normally driven by a synchronous electric motor operated by current flow from the commercial light and power line, and wherein is provided a stand-by or auxiliary motor which operates to drive its time indicating element at the correct time rate in case the synchronous motor fails to operate effectively.

An object of this invention is to provide a clock of the above type which is of improved construction and arrangement of parts.

Another object is to provide a clock of the type mentioned above, which operates with a high degree of accuracy at all times, and one wherein the changeover from synchronous motor drive to stand-by motor drive, and vice versa, is accomplished in a highly effective and efficient manner and with a minimum of variation in the time keeping rate of the clock.

A further object is to provide a clock of the type indicated, wherein a spring-driven motor is used as the stand-by and wherein an improved and simple means is provided for winding the spring-driven motor from the electric motor, which means utilizes a minimum of power.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a top plan view showing one preferred embodiment of a clock constructed in accordance with the present invention, the outer casing of the clock being omitted.

Fig. 2 is a front elevation of the clock as shown in Fig. 1;

Fig. 3 is a vertical sectional view, the section being taken on the line 3—3 of Fig. 1;

Fig. 4 is a fragmentary vertical section taken on the line 4—4 of Fig. 1;

Fig. 5 is a fragmentary vertical section taken at right angles to Figs. 3 and 4, the section being indicated generally by the broken line 5—5 in Fig. 2, and certain of the parts being broken away and shown in section in a slightly different plane so as to illustrate certain structural details more clearly;

Fig. 6 is a fragmentary horizontal section, the plane of the section being indicated by the line 6—6 of Fig. 5;

Fig. 7 is an enlarged fragmentary vertical sec-

2

tion, the plane of the section being indicated generally by the line 7—7 of Fig. 6;

Fig. 8 is a fragmentary vertical sectional view showing structural details of the means for winding the power spring of the spring-driven motor, certain of the parts being partially broken away to illustrate the structure more clearly, the plane of the section being indicated by the line 8—8 of Fig. 5; and

10 Fig. 9 is a fragmentary vertical section taken on the line 9—9 of Fig. 8.

From the drawings, it will be observed that the present invention has been shown as embodied in a clock of the type known as a master clock which is constructed and adapted to form a part 15 of a clock system, which system also includes one or more secondary clocks located at points remote from the master clock. An example of a master clock and an explanation how such a clock 20 functions in a clock system are disclosed fully in the U. S. patent to Larrabee, No. 1,878,931, granted September 20, 1932.

Generally speaking, a master clock of the type disclosed operates to send electrical impulses at 25 regular intervals of time to all of the secondary clocks and each secondary clock is advanced a predetermined amount upon receiving each impulse. In addition to this, the master clock at certain predetermined intervals of time automatically regulates, or effects synchronization with the master clock of any of the secondary clocks which may be fast or slow. It is noted, however, that while the present invention has been shown and described as embodied in a master clock of 30 the type shown in the above identified Larrabee patent, it is not to be considered as being limited in all of its aspects to an application of that type, for it might also be embodied in other kinds of clocks without departing from the spirit there- 35 of or from its intended scope.

Referring now in detail to the construction illustrated, the reference numeral 50 indicates the front support plate and the numeral 51 the rear support plate of the master clock. The plates 50 45 and 51 are held in fixed spaced relation by the usual pillars 52. The clock comprises a time indicating train which consists of a driven shaft 53 supported for rotation by the two plates 50 and 51. The driven shaft is journaled at its rear end 50 in an axial bearing opening 54 provided in a bushing 55 which is in turn journaled for rotation in a sleeve 56, the latter being fixed to the rear support plate 51 (see Figs. 5 and 7). The driven shaft 53 is journaled at its forward end in the 55 front support plate 50. As will appear more fully

hereinafter, the driven shaft 53 is driven at the rate of one revolution per minute. The shaft 53 can therefore, be considered as the seconds shaft of the time indicating train. A wheel 57 having thirty ratchet teeth thereon is fixed to the shaft 53. Also, a cam 29 is fixed to the forward extension of the shaft 53. As will appear more fully hereinafter, the ratchet wheel 57 operates the rapid impulse contacts 17 of the clock and the cam 29 the minutes impulse contacts 28.

In addition to the shaft 53, the time indicating train also includes a gear 60 fixed to the forward extension of the driven shaft 53 and meshing with a second gear 61 of the same size as gear 60 and fixed to a sleeve 62 journaled for rotation on a bushing 63 which is, in turn, fixed at its rear end to the front support plate 50 (see Fig. 5). Also fixed to the rotatable sleeve 62 are a pair of planet arms 64 carrying, respectively, a pair of planet pinions 65, the latter being journaled for rotation on studs carried by the outer ends of their respective arms. The pinions 65 mesh with a sun gear 66 fixed to the forward end of the fixed bushing 63 and also with a second sun gear 67 fixed to a bushing 68 which is journaled for rotation on the forward extension of a support shaft 69, the latter being supported for rotation at its rear end by the plate 51 and at its forward end in the fixed bushing 63 carried by the front support plate 50.

The stationary sun gear 66 is provided with sixty-one teeth and the rotatable sun gear 67 with sixty teeth. Thus, for each revolution of the driven or seconds shaft 53, in a clockwise direction, the gear 61 and planet arms 64 are rotated one revolution in a counterclockwise direction and the sun gear 67 and bushing 68 are rotated one tooth or one-sixtieth of a revolution in a clockwise direction. Consequently, the sun gear 67 and bushing 68 rotate at the rate of one revolution per hour which is the same as the minutes hand on the conventional clock.

An outer sleeve bushing 70 is rotatably supported on the bushing 68 and a pair of cams 40 and 41 are fixed to the outer sleeve bushing 70. As will appear more fully hereinafter, the cams 40 and 41 control the opening and closing of the synchronizing contacts 38 and 39 of the clock. Also, a minutes indicating disk 71 is fixed, by a nut 12 screwed to the end of the shaft 69, to the forward edge of the outer bushing 70 (see Figs. 1 and 5). A fixed pointer 73 carried by the plate 50 cooperates with the minutes disk 71 to indicate the time setting of the clock (see Fig. 2). The outer sleeve bushing 70 is connected by a friction drive with the rotary sun gear 67 and inner bushing 68. The friction drive comprises a cup-shaped spring element 74 encircling the bushing 68 and fixed to the side of the sun gear 67 and bushing 68 so as to rotate therewith. The element 74 includes a resilient rim portion 75 which may be slit along radial lines to form spring fingers frictionally engaging a fibre washer 76 encircling the bushing 68. The rim 75 holds the washer 76 in frictional driving engagement with the side of the cam 40. The frictional driving connection just described permits rotary adjustment of the cams 40 and 41 and the minutes indicating dial 71 with respect to the rotary sun gear 67 for the purpose of changing the time setting of the clock.

As explained at the outset, the clock is provided with a synchronous electric motor driving train which normally operates the time indicating train at a fixed time rate from the commercial AC

power and light line, and the clock is also provided with a standby or auxiliary motor driving train which operates the time indicating train at its correct time rate upon a failure in current supply to the synchronous electric motor.

The synchronous electric motor driving train comprises a conventional form of synchronous electric motor 78 supported by suitable brackets from the rear support plate 51 and having its power shaft connected by a suitable coupling 79 with a drive shaft 80 which is journaled for rotation in spaced brackets 81 extending rearwardly from the rear support plate 51. As indicated in Fig. 1, the motor 78 is connected by wires 82 and 83 to a convenient source of AC current. The drive shaft 80 is formed intermediate its ends with a worm 84 meshing with a worm wheel 85, the latter being rotatably supported on a fixed stud 86 carried by the rear plate 51 (see Figs. 1, 4 and 5). A spur gear 87 is fixed to the worm wheel 85 and meshes with a second spur gear 88 which is fixed to the rear end of bushing 55 previously described, as being rotatably supported in the sleeve 56 carried by the rear support plate 51 (see also Fig. 7).

The bushing 55 is the terminal element of the just described power transmitting gear train driven from the motor 78. The design of the electric motor 78 and of the gears 84, 85, 87 and 88 is such that when the motor is connected to the commercial AC light and power line, the bushing 55 will be operated at the fixed time rate of one revolution per minute.

The stand-by motor driving train comprises as its source of power, a spring motor 90 which comprises a power shaft 91 rotatably supported at its ends by the support plates 50 and 51, a spiral power spring 92, and a pair of spaced parallel disks 93 and 94, respectively (see Figs. 5, 8, and 9). The inner end of the power spring 92 is fixed to the power shaft 91 and the outer end of the spring is fixed to one of a plurality of spring restraining studs 95 extending forwardly from the disk 93. The disk 93 is fixed to one end of a hub 96 journaled on the shaft 91. A ratchet wheel 97 is fixed to the other end of the hub 96 so that the wheel 97 and disk 93 rotate together.

In accordance with the present invention, the power spring 92 is kept wound by the operation of the synchronous electric motor 78. A worm 98 is formed on the outer end of the drive shaft 80 and meshes with a worm wheel 99 fixed to a rearward extension of a cam shaft 100, the latter being journaled for rotation in the support plates 50 and 51 and having fixed thereto a cam 101. Thus, as long as the electric motor 78 operates, the cam 101 is rotated through the drive mechanism just described.

A vertically arranged pawl-carrying rock lever 103 is pivoted at its lower end on a stud 104 extending forwardly from the rear plate 51 (see Fig. 8). A rotary cam follower 105 is journaled on a stud 106 extending from the upper part of the lever 103 and engages the face of the cam 101. A pawl 107 is pivoted at one end to the upper end of the lever 103 and is provided at its other or outer end with a hook or tooth 108 adapted to engage the teeth of the ratchet wheel 97. A tension spring 109 connected at its upper end to a mid point on the pawl 107 and at its lower end to the lever 103, serves to hold the hook 108 in engagement with the teeth of the ratchet wheel 97. A relatively strong tension spring 110 is connected at one end to the upper end of lever 103 and at

its other end to a fixed stud 111 projecting forwardly from the rear plate 51.

The spring 110 functions to hold the cam follower 105 firmly against the face of the cam 101, and thereby acts to pull the lever 103 and pawl 107 to the left, as viewed in Fig. 8, when the cam 101 is in that part of its revolution where the height of the cam face engaging the follower 105 is decreasing. With the hook 108 engaging a ratchet tooth, this movement of the lever 103 to the left, results in the rotation of the ratchet wheel 97 and disk 93 is a counter-clockwise direction to wind the power spring 92. When the height of the cam face engaging the follower 105 is increasing, the lever 103 is moved to the right, as viewed in Fig. 8, against the force of the spring 110 and the hook 108 rides over the ratchet to engage a new tooth. A dog 112 pivoted to a fixed stud 113 and held in engagement with the ratchet 97 by a tension spring 114 serves to prevent rotation of the ratchet wheel in a clockwise or unwinding direction when the cam 101 moves the pawl 107 to the right to engage a new tooth.

From the foregoing, it is apparent that when the power spring 92 approaches a fully wound condition, it resists at a progressively increasing rate the winding force applied by the spring 110; and, when the spring 92 is fully wound, the force of the spring 110 is completely overcome. As the power spring 92 approaches being fully wound, a condition is reached where the spring 110 can not pull the lever 103 and pawl 107 the full distance to the left and the cam 101 will then leave the follower 105. From the point where this condition begins, the spring 110 moves the lever 103 to the left a less distance on each succeeding revolution of the cam until the spring 92 is fully wound. When the latter occurs, there is no movement of the lever 103 to the left. As the amount of work done by the cam 101 is a function of the distance it has to move the lever 103 to the right, it follows that the cam 101 does less and less work as the power spring 92 approaches being fully wound, and when the power spring is fully wound, the rotating cam performs no further work. It is believed to be apparent that because of this novel construction and arrangement, the portion of the power consumption of the electric motor which is required to wind the power spring is kept at a minimum.

The stand-by motor driving train also comprises a series or train of power transmitting gears which are continuously operated from the power shaft 91 at a definite time rate controlled by an escapement means. This gear train comprises a first gear 115 fixed to the power shaft 91 and meshing with a second gear 116 fixed to one end of a sleeve bushing 117 rotatably mounted on the shaft 69. A third gear 118 is fixed to the other end of the bushing 117 and meshes with a pinion 119 fixed to a shaft 120 rotatably mounted at its ends in the support plates 50 and 51. Also fixed to the shaft 120, is a gear 121 which meshes with a pinion 122 fixed to a sleeve 123 rotatably mounted on the driven shaft 53 of the time indicating train (see Figs. 5, 6 and 7).

The sleeve 123 is the terminal element of the power transmitting gear train just described and is continuously operated by the power spring 92, under the control of an escapement means, at the definite time rate of one revolution per minute. The controlling escapement means is of the conventional type and comprises an escapement drive wheel 125 fixed to the sleeve 123 and meshing with a pinion 126 fixed to a sleeve 127

journaled on a shaft 128, the latter being supported at its ends by the plates 50 and 51. Also fixed to the sleeve 127 and pinion 126 is an escape wheel 129. Cooperating with the escape wheel 129 is the usual verge 130 mounted for oscillation on a verge shaft 131 carrying the oscillating verge lever 132 which cooperates in the usual manner with the impulse pin 133 on the balance wheel 134. The balance wheel 134 is mounted on the balance wheel shaft 135 supported at its ends by the front and rear support plates 50 and 51. A more detailed description of the escapement means is considered unnecessary as it is of the conventional type and its function and operation will be readily understood by those skilled in this art.

In accordance with the present invention, there is also provided a selective clutch mechanism, indicated generally at 140, which during normal operation connects the driven shaft 53 to the bushing 55 which is operated by the electric motor 78; and which, when there is a failure in the current supply to the motor 78, automatically disconnects the shaft 53 from the bushing 55 and connects the driven shaft 53 to the sleeve 123, the latter being the terminal element on the stand-by motor driving train and being continuously rotated by the spring driven motor 90 in the manner previously described.

As shown in Figs. 4, 5, 6, and 7, the clutch 140 comprises first and second clutch members 141 and 142 respectively, which are arranged in spaced parallel relation and are fixed, respectively, to the front end of the bushing 55 and the rear end of the sleeve 123. The clutch members 141 and 142 are shown as being in the shape of circular plates or disks and are both coaxially arranged with respect to the driven shaft 53, and each member is provided on the face thereof which is adjacent the other member, with an annular series of clutch teeth 143.

The clutch 140 also comprises a disk-like element 144 arranged between the members 141 and 142 and having a pin-and-slot connection with the driven shaft 53 so that the element 144 will always rotate with the shaft 53 and, at the same time, can be shifted axially of the shaft towards the member 141 or the member 142. Specifically, the element 144 is fixed to a sleeve bushing 145 mounted on the shaft 53 and the bushing 145 is provided with a longitudinal slot 146 receiving a pin 147 fixed to and extending radially from the shaft 53. Thus, the clutch element 144 may be shifted axially of the driven shaft a distance determined by the length of the slot 146.

Projecting from opposite sides of the peripheral portions of the element 144, are spring clutch fingers 149 and 150, respectively, which are adapted to engage selectively the teeth 143 of member 141 and member 142. In the drawings, the parts are shown in their normal operating position with the finger 149 in engagement with the teeth 143 of the first clutch member 141 which is driven in the manner previously explained by the electric motor. Thus, as shown, the shaft 53 is being driven through the element 144 and finger 149 at its designated time rate of one revolution per minute. At the same time, the sleeve 123 and the second clutch member 142 are being continuously operated at this same rate from the spring motor 90.

The finger 149 is held in engagement with the teeth of the first clutch member 141 by a magnet 152 energized from the AC power supply wires 75 82 and 83 leading to the motor 78 (see Fig. 1).

The armature 153 of the magnet forms a part of a lever 154 pivoted to move about the axis of a vertical pin 155 which is carried by spaced brackets 156 extending forwardly from the rear support plate 51. The lever 154 also comprises a pair of spaced bars 157 and 158, respectively, extending horizontally from the armature 153 and receiving intermediate their ends the pivot pin 155. The outer ends of the bars are turned inwardly toward one another to form opposed fingers 159 and 160, respectively, which are formed with slots 161 receiving the upper and lower parts of the movable clutch element 144.

From the foregoing, it is apparent that as long as the magnet 152 remains energized, the clutch element 144 is held by the lever 154 in driving engagement with the first clutch member 141. Upon a failure in current supply, the magnet 152 is deenergized and a tension spring 162 moves the lever 154 about its pivot pin 155 and the element 144 is thereby shifted axially of the shaft 53 to disconnect the finger 149 from the member 141 and connect the finger 150 with the continuously rotating clutch member 142 so that the shaft 53 will then be driven from the spring motor 90. When the current again flows to the motor 78 and magnet 152, the latter will shift the lever 154 and clutch element 144 against the force of the spring 162 and back to the normal operating position shown in the drawings.

The clock construction described above has many advantages not found in prior clocks. The clock of the present invention operates with a relatively high degree of overall accuracy. During normal operation, its time rate is controlled directly by the regulated frequency of the AC power and light line in a manner well known to those skilled in this art. The simple form of clutch 140 provides an effective means for instantaneously shifting from electric motor drive to spring motor drive and vice versa. Because the spring motor driving train is operating continuously while the electric motor is driving the clock, the time rate of the spring motor train can be regulated so that it will operate with the same degree of accuracy as any clock operated by a spring motor. Furthermore, if the spring motor were idle and started when the current failed, there would be a definite lag before the spring motor train would operate. There would also be a possibility that the spring motor would not start. Thus, there is provided a stand-by source of power for the time indicating train which is always available and dependable and which is instantaneously connected to the time indicating train by the clutch 149 the moment the electric power supply fails.

Because the clock of the present invention operates with a high degree of accuracy, it is well adapted for use as a master clock which, as stated previously, forms a part of a clock system and functions to control the operation of one or more secondary clocks in a manner fully disclosed in the U. S. patent to Larrabee, identified above. Herein, the clock system and the manner in which the secondary clocks are operated and regulated, are not disclosed as it is considered unnecessary to an understanding of the present invention. However, in the accompanying drawings, the master clock has been shown as provided with certain electrical contacts and operating means for closing and opening the contacts, so that the clock disclosed herein can function in a clock system in the same manner as the master clock of the Larrabee patent. Where it is proper, the

same reference characters are used herein to identify these contacts and their operating elements as are used to identify the corresponding parts in the Larrabee patent.

The contacts 28 are the minutes impulse contacts and are normally open. They are closed once each minute to send an electrical impulse to each of the secondary clocks of the system for advancing them. The means for operating the contacts comprises a cam follower 32 pivoted at one end to a stud 31 and engaging at its other end the face of cam 29 mounted on the driven shaft 53 which makes a complete revolution each minute (see Fig. 2). A three-arm lever 33 is pivoted at 34 on the follower 32 and one arm is provided with a contact actuating element 35 engaging the lower member of the spring contacts 28. An arm 36 engages at its outer end the face of the cam 29 and is held in contact therewith by a tension spring 37 connecting a fixed stud and the third arm of the member 33. The spring 37 also holds the follower 32 in contact with the cam 28. The arm 36 is slightly shorter than the follower 32 so that it drops off the high point of cam 29 just before the follower 32. When both arm 36 and follower 32 are engaging either the high point or the low point of the cam 29, the element 35 holds the contacts 28 open; but, when the arm 36 drops off the high point of the cam and the follower 32 is engaging the high point, the spring 37 rotates the three-arm lever clockwise as viewed in Fig. 2 so that the element 35 closes contacts 28. An instant later when follower 32 also drops off the high point, the contacts 28 are again opened by the element 35.

The synchronizing contacts 38 and 39 are actuated by the cams 40 and 41 mounted on the sleeve 70 which makes one revolution each hour. Cooperating with the cam 41 is a cam follower 43 similar to follower 32, just described. A three-arm lever 44, similar to lever 33, is pivoted on the follower 43 and has an arm 47 engaging the face of the cam 40. Another arm of the lever 44 carries an insulating disk 45 which bears on the underside of the lower of the two central spring contact members of contacts 38 and 39. The two central spring members are biased downwardly so that when all restraint on the members is removed, the lower contacts 39 will close. A tension spring 46 connected a fixed stud and the third arm of lever 44, holds the arm 47 and follower 43 in contact with the faces of cams 40 and 41.

For each revolution of the sleeve 70, the cams 40 and 41 operate to provide three operating positions of the contacts 38 and 39; viz., the closing of contacts 39, the closing of contacts 38, and a mid position where both contacts 39 and 38 are held open. In order to accomplish this, the cam 40 is provided with two steps of different heights and the cam 41 with only one step. When the follower 43 and arm 47 engage the highest points of their respective cams 41 and 40, and when both follower 43 and arm 47 rest on the lowest points of their cams, the contacts 39 are closed. The cams 40 and 41 are so positioned on the sleeve 70, that this latter condition occurs during the period beginning with each hour and ending with about forty-nine minutes past each hour. The upper contacts 38 are closed when the follower 43 is on the highest point of cam 41 and when the arm 47 is on the lowest point of cam 40. The latter occurs during the period beginning about thirty seconds before each hour. Neither contacts 38 nor contacts 39 are closed

when the follower 43 is on the high point of cam 41 and the arm 47 is engaging the intermediate step of cam 40. The latter condition occurs from about forty-nine minutes after each hour until about thirty seconds before the next hour.

The rapid impulse contacts 17, are operated once each two seconds by the thirty tooth ratchet wheel 57 fixed to the driven shaft 53. As explained in the aforementioned Larrabee patent, during the thirty second interval that the contacts 38 are closed and the contacts 39 are open, the circuit is under the control of contacts 17 and the latter then operate to send rapid electrical impulses to any of the secondary clocks which are slower than the master clock, for the purpose of advancing such slow clocks to agree with the time setting of the master clock. The upper of contacts 17 is mounted on a spring blade 170 and the lower of contacts 17 is mounted on a second spring blade 171 and the blades 170 and 171 engage at their outer ends the teeth of ratchet wheel 57. The relative lengths of blades 170 and 171 are such that they both engage the same ratchet tooth for an instant, then the blade 171 drops off such tooth onto the next tooth while the blade 170 remains in engagement with such tooth, and then the blade 170 drops off onto the next tooth. When both blades 170 and 171 engage the same tooth, the contacts 17 are closed, and when the blades 170 and 171 engage different teeth, the contacts 17 are open.

While there have been shown and described and pointed out the fundamental novel features of the invention as applied to a single modification, it will be understood that various omissions and substitutions and changes in the form and details of the device illustrated and in its operation may be made by those skilled in the art, without departing from the spirit of the invention. It is the intention, therefore, to be limited only as indicated by the scope of the following claims:

What is claimed is:

1. In a clock, a time indicating element; motion transmitting means for operating said element and comprising a driven shaft; selective clutch mechanism comprising first and second clutch members journaled to rotate about the axis of said driven shaft and being spaced axially from one another, and a clutch element mounted on said driven shaft between said first and second clutch members and being secured to said shaft for rotation therewith and being shiftable axially of said shaft into selective clutching en-

gagement with said first and second clutch members; a first clock driving mechanism operable at a definite time rate and including a synchronous electric driving motor having a driving connection with said first clutch member; a second clock driving mechanism operating continuously and at the same rate as said first driving mechanism and including a power spring and a gear train having a driving connection with said second clutch member for continuously rotating the latter; and current responsive means operable upon a flow of electric current to said synchronous motor to shift said clutch element into clutching engagement with said first clutch member and operable upon a failure in current flow to shift said clutch element into clutching engagement with said second clutch member.

2. Apparatus according to claim 1 wherein each of said first and second clutch members comprises a clutch disk mounted for rotation on said driven shaft and provided on the face thereof of which is adjacent the shiftable clutch element with a series of clutch teeth extending circumferentially about the axis of said driven shaft, and wherein said shiftable clutch element is provided on opposite sides thereof with spring fingers extending outwardly therefrom and toward both disks and being so constructed that as said element is moved toward one of said disks the fingers operatively engage the clutch teeth on said one disk and are disengaged from the other disk and so that as said element is shifted in the opposite direction toward said other disk the fingers operatively engage the clutch teeth thereon and become disengaged with the teeth of said one disk.
